(57) **CLAIM**

The ornamental design for mixing faucet, as shown and described.

DESCRIPTION

FIG. 1 is a perspective view of the mixing faucet showing a new ornamental design thereof;

FIG. 2 is a front elevation view of the mixing faucet shown in FIG. 1;

FIG. 3 is a rear elevation view of the mixing faucet shown in FIG. 1;

FIG. 4 is a right side elevation view of the mixing faucet shown in FIG. 1;

FIG. 5 is a left side elevation view of the mixing faucet shown in FIG. 1;

FIG. 6 is a top plan view of the mixing faucet shown in FIG. 1; and,

FIG. 7 is a bottom plan view of the mixing faucet shown in FIG. 1.

The broken lines are included for the purpose of illustrating portions of the mixing faucet that forms no part of the claimed design.
